UNITED STATES PATENT OFFICE

2,026,191

VALVE FOR SPRAY GUNS

William L. Rowland, Mosier, Oreg.

Application August 4, 1934, Serial No. 738,465

1 Claim. (Cl. 299—150)

This invention relates generally to spraying apparatus such as is used by orchardists, and particularly to a spray gun.

The main object of this invention is the provision of a spray gun having a special form of control valve and means for operating same.

The second object is to provide a control for the spray valve which will be quick in operation, not easily rendered inoperative and economical in its handling of the spray materials.

These, and other objects, will become more apparent from the specification following as illustrated in the accompanying drawing, in which:

Fig. 1 is a plan of the device.

Fig. 2 is a side elevation thereof.

Fig. 3 is a longitudinal section through the valve.

Fig. 4 is an end elevation showing the device with the supply line connected to the end of the handle.

Fig. 5 is a section taken along the line 5—5 in Fig. 3.

Similar numbers of reference refer to similar parts throughout the several views.

Referring in detail to the drawing, there is shown a barrel 10 of a spray gun whose nozzle 11 is threaded onto the barrel 10. The nozzle 11 has formed therein a chamber 12 which contains a guide 13 having a longitudinally slidable stem 14 which projects through the mixing disk 15 whose openings 16 are preferably spirally disposed about the axis of the stem 14.

Against the disk 15 is placed a packing ring 17 on the outside of which is a thin plate 18 provided with a central opening 19 through which the spray material is discharged. The point 20 is preferably of a size to pass through the opening 19 when the valve is closed, the closing action itself being provided by means of a resilient tip 21 which surrounds the point 20.

The plate 18 is held against the packing 17 by means of a threaded cap 22 which is screwed upon the end of the nozzle 11.

The barrel 10 is threaded into the body 23 which contains a chamber 24 to which spray material may be admitted through the branch inlet 25 from the spray line or hose 26, preferably provided with a swivel coupling (not shown).

In the opposite end of the body 23 and in line with the barrel 10 is threaded the tubular handle 27 whose outermost end 28 is provided with a plug 29 which is used only when the spray is admitted by way of the hose 26. Where it is desired to have the spray enter the gun by way of the handle 27 a plug 30 is inserted into the branch 25 and the connecting pipe 31 is inserted in place of the plug 29 (as shown in Fig. 4).

The stem 14 extends through the chamber 24

into the handle 27. A spring 32 is placed around the end of the stem 14, one end of which re-acts against the plug 29 and the other end of which re-acts against the washer 33 which bears against the pin 34 on the stem 14.

Transversely journaled in the body 23 is a rock shaft 35 around the opposite ends of which are placed the stuffing boxes 36. The projecting ends of the shaft 35 have secured thereto the ends of the operating lever 37 which is bent (as shown) to suit the convenience of the operator.

Mounted on the shaft 35 is a forked arm 38 whose pin 39 passes through the stem 14.

The operation of the device is as follows: Assuming the parts to be in the position shown in Fig. 2 and it is desired to use the gun for spraying purposes it is only necessary for the operator to press the lever 37 toward the handle 27, which will cause the shaft 35 to rock and, through the forked arm 38, impart a sliding motion to the stem 14, the amount of which varies with the movement of the lever 37, permitting the spray to be discharged from the opening 19 until the lever 37 is released and returns to a rest position, under the action of the spring 32.

In spray guns now in common use it is the customary practice to control the movement of the valve by means of a screw, which motion is not only slow but also tends to wear the tip 21, and in addition thereto the screw type of control is subject to automatic opening under pressure, thereby causing an objectionable waste of materials.

It will be noted that the point 20, while not serving as a closure for the outlet opening 19, does serve to maintain a fixed diameter of outlet opening thereby preventing an accumulation of spray materials or foreign substances in the opening 19.

I claim:

A spray gun including a body having a handle mounted at one end thereof and a barrel at the opposite end thereof in alignment with said handle said body, handle and barrel constituting a valve casing, means for admitting spray material to the interior of said body, a nozzle on the outer end of said barrel communicating with said body by way of said barrel, said nozzle having an outlet opening therein, a valve stem lying wholly within said casing and slidably movable therein having a soft tip forming a closure for said nozzle outlet opening, a rock shaft mounted in said body having a forked arm connected to said stem, a lever on the outside of said body adjacent to said handle connected to said rock shaft, and a spring within said handle for urging said stem to move its soft seat over the outlet opening in said nozzle.

WILLIAM L. ROWLAND.
